Primary Examiner — Richard Kearney*Assistant Examiner* — Benjamin M Weeks(74) *Attorney, Agent, or Firm* — Dunlap Bennett & Ludwig, PLLC(57) **CLAIM**

The ornamental design for a shepherds hook with post coupler, as shown and described.

DESCRIPTION

FIG. 1 is a front perspective view of a shepherds hook with post coupler, showing my new design;

FIG. 2 is a front elevation view thereof;

FIG. 3 is a rear elevation view thereof;

FIG. 4 is a left side elevation view thereof, the ride-side elevation being a mirror image thereof;

FIG. 5 is a top plan view thereof; and,

FIG. 6 is a bottom plan view thereof.

The broken lines shown in the drawings depict portions of the shepherds hook with post coupler that form no part of the claimed design.
